UNITED STATES PATENT OFFICE.

ALFRED H. HAAG, OF BALTIMORE, MARYLAND, ASSIGNOR OF ONE-HALF TO E. HAYWARD FAIRBANKS, OF MERCHANTVILLE, NEW JERSEY.

COMBINED PHONOGRAPH AND RADIO AND COORDINATING UNIT THEREFOR.

Application filed October 23, 1925. Serial No. 64,296.

My invention relates to a new and useful apparatus wherein a talking machine or phonograph and a wireless receiving set, each of any conventional type, are so combined into one unitary construction, through the medium of a novel coordinating unit, also of my invention, as to permit the operation of either the talking machine or the wireless receiving set, at will, by the mere movement of the handle or knob of an electrical contacting device, into either one of two operating positions.

My invention further relates to a novel apparatus wherein the phonograph record is reproduced through an electric circuit, which electric circuit is connected to a coordinating unit, to which coordinating unit is also connected any suitable or desirable wireless receiving set and a common loud speaker.

My invention further relates to a novel combined phonograph and radio apparatus of the character hereinabove stated, in which a phonograph record reproducing electrical circuit and the output circuit of a radio receiving set are connected to a common coordinating unit and wherein a common loud speaker is also connected to said coordinating unit and wherein, moreover, the volume of sound emitted from said loud speaker horn, from the phonograph, may be regulated or controlled through a rheostat, also forming part of my novel coordinating unit.

My invention relates, more particularly, to a novel combined phonograph and radio apparatus wherein any radio receiving set may be utilized and incorporated in my novel combination apparatus, without any alteration in the receiving set, and wherein, moreover, the phonograph record is reproduced through a simple electrical circuit without the aid of any amplifying means, such as a conventional vacuum tube.

My invention further relates to a novel cabinet construction adapted to house a phonograph or talking machine, a wireless receiving set, a loud speaker horn and a coordinating unit for said talking machine and said radio set, and whereby said elements of my novel apparatus are arranged compactly and in a position to be most adapted for the operator, and whereby, moreover, the

operating parts of my novel apparatus may be concealed from view when not in use, by suitable doors or closures, thereby to provide not only a housing for my novel combined radio and phonograph apparatus, but also to produce an artistic piece of furniture.

My invention further consists in a novel manner of collocating a speaker, preferably of the cone type in the talking machine compartment, in such a way that the back of said compartment acts as a sounding board to augment the reproduced sounds emanating from the loud speaker common to the radio and phonograph.

My invention further consists in a novel manner of pivotally supporting a loud speaker of the character above referred to, so that it can be swung outwardly to give ready access to the loud speaker unit, when desired.

My invention further consists in novel means for enabling an electrically operated phonograph record reproducer and its loud speaker to be readily electrically connected with any standard or conventional radio or wireless telegraph receiving apparatus.

My invention further consists of a novel manner of mounting the switch which controls the radio and phonograph reproductions, and a novel manner of enabling said switch to be assembled and electrically connected with said radio and phonograph.

For the purpose of illustrating my invention, I have shown in the accompanying drawings forms thereof which are at present preferred by me since they will give in practice satisfactory and reliable results, although it is to be understood that the various instrumentalities of which my invention consists can be variously arranged and organized and that my invention is not limited to the precise arrangement and organization of these instrumentalities as herein shown and described.

Referring to the drawings:—

Figure 1 represents a front elevation of a cabinet containing my novel construction of combined radio and phonograph, embodying my invention, the doors being shown closed.

Figure 2 represents a view similar to Figure 1 showing the doors open.

Figure 3 represents a horizontal section on line 3—3 of Figure 1.

Figure 4 represents a vertical section, on a reduced scale, on line 4—4 of Figure 2.

5 Figure 5 represents a front elevation of another embodiment of my invention, the upper cover or lid being shown as standing vertical or open.

10 Figure 6 represents a vertical section on line 6—6 of Figure 5.

Figure 7 represents a rear view of my novel coordinating unit.

Figure 8 represents an end elevation of my novel coordinating unit.

15 Figure 9 represents a schematic wiring diagram of my novel coordinating unit.

In carrying out my invention, I may obviously house the same in any suitable cabinet, but I preferably employ the cabinet 20 1 shown, which comprises the upper compartment 2, formed by the lower horizontal shelf 3, the rear wall 4, the fixed top 5, and the front upper doors 6, the latter being reticulated or consisting of grills, having, if 25 desired, a rear facing of silk or similar material through which the reproduced sounds emanate. 10 designates the side panels of the compartment 2.

30 The shelf 3 serves as a motor board for the talking machine and supports the motor 7, which drives the spindle 8, carrying the turn table 9. The rear wall 4 supports the loud speaker 11, which may be of any conventional type, and is provided with the 35 phone unit 12, as is customary. Compartment or alcove 2 contains both a conventional loud speaker and talking machine equipment, which in the present instance is provided with an electrical reproducer 13, carried by the arm 14, whose rear end is 40 pivotally mounted in the bracket 15.

The left hand side of the shelf 3 can be utilized as a writing desk, and is provided, 45 at its rear, with the ink stand 16 and the grooves 17 for the reception of a pen and pencil, while the needle cups are indicated at 18, (as seen in Figure 3). When the doors 6 are closed, as seen in Figures 1 and 50 4, they serve to conceal the contents of the chamber 2, but still permit the reproduced sounds to emanate therethrough from either the phonograph or radio, since the loud speaker is common to both, as will be hereafter explained. When the doors 6 are open, 55 as seen in Figure 2, ready access can be had to the phonograph and loud speaker.

The loud speaker 11 is preferably hinged to the back 4, as indicated at 19, in Figure 2, and is locked in fixed position by the tension catch 20, of any conventional type, and when it is desired to get access to the phone unit 12, the loud speaker can be readily swung forwardly, upon the releasing of the catch 20.

60 21 designates the radio chamber, formed

between the partition or shelf 3 already described, and the shelf 22 below, the front of said radio chamber being closed by the drop door 23, hinged at the points 24. Behind the drop door is the control panel 25, 70 of the coordinating unit, which is preferably positioned at the right of the radio chamber, as will be understood from Figure 2, the left hand portion of the radio chamber 21 being provided with the radio panel 26. 75

The right hand coordinating unit, carried by the control panel 25, consists of the rheostat 27, having the control knob 28 which controls the volume of electrically reproduced sounds of the phonograph. On the 80 coordinating unit panel 25, there is also mounted the operating knob or handle 29 of the switch or contacting device 59, which in its extreme positions controls the circuit of the phonograph or the radio. In the 85 present construction, when the switch handle is thrown to the left, as seen in Figure 2, to the radio indicia 30, the radio circuit is closed and the radio receiving set is functioning. When the switch handle 29 is 90 thrown to the right of the position seen in Figure 2, to the phonograph indicia 31, the radio circuit is open and the phonograph circuit is closed, so that the electrical phonograph reproducer is functioning; it being 95 understood that the loud speaker 11 is common to both the radio and the phonograph circuits, and the manner of opening and closing the circuit of each being apparent from the wiring diagram seen in Figure 9. 100

The lower compartment formed between the bottom 33 and the upper shelf 22, is divided by the central vertical partition 32, into the left and right hand compartments 34 and 35, adapted for the batteries 36 and 105 37 and record albums 38. The compartments 34 and 35 are closed by the doors 39 and 40.

In the constructions seen in Figures 5 and 6, I have shown the right hand top portion 110 or lid 41, hinged at the points 42, and the loud speaker designated as 43, is hinged at the points 44 to the under side of said lid, which is adapted to stand vertical when the phonograph or radio is functioning, said 115 loud speaker being common to both, as in the construction already described. The left hand top portion 45, seen in Figure 5, is preferably stationary or fixed.

The electrical coordinating unit, mounted 120 upon the panel 25, is composed of the induction coil or transformer 50, having the primary coil 51 and a secondary coil 52. One side of the primary coil 51 is connected through suitable connections 53 to one of 125 the two binding posts or plug contacts 54 adapted to receive the lead wires from the phonograph reproducer; the other of said binding posts or plug contacts 55 being connected directly to one side of the storage 130

batteries or other source of electric current supply 56, through suitable connections 57 and the binding post 58. The coordinating unit includes the multiple switch or contacting device 59, having the three stationary contacts 60, 61 and 62 and having the two movable spring contacts 63 and 64 which are moved in unison by an insulating roller 65 carried by the handle 29 pivoted at 66. The movable contact 63 is juxtaposed to said stationary contact 60, while the movable contact 64 is interposed between the two stationary contacts 61 and 62 in such a manner that in the neutral position thereof, shown in Figure 9, it will contact with neither one of said stationary contacts but will contact with either one or the other, upon the displacement to one or the other side. The second terminal of the primary winding 51 of the induction coil 50, is connected through suitable connections 67 to said first mentioned movable contact 63 of the switch 59, while the corresponding juxtaposed stationary contact 60 is connected through the connection 68 to a suitable rheostat 27, also forming part of said coordinating unit; said rheostat being in turn connected through the connection 69 and the binding post 70, to the opposed side of said storage battery 56. Thus, when the handle 29 is moved in the direction of the arrow 71, the movable contact 63 will make contact with the stationary contact 60 and thereby complete the electrical circuit through the record reproducer connected to the binding posts 54 and 55, the primary winding 51 of the induction coil 50, the rheostat 27, and the storage battery 56. The second stationary contact 61 is connected directly to one side of the secondary winding 52 of said induction coil 50 through a suitable connection 72; the opposite side of said secondary winding being connected directly to one of the loud speaker binding posts or plug contacts 73, through a suitable connection 74. The second movable contact 64 is connected directly to the second loud speaker binding post or plug contact 75 through the connection 76. Thus, upon moving the handle 29 in the direction of the arrow 71, there will also be established a complete electrical circuit through the loud speaker contacts or binding posts 73 and 75, and the secondary winding 52, through said stationary and movable contacts 61 and 64 respectively, thereby effecting an operative electrical connection from the record reproducer to the loud speaker, in the extreme right hand position of the handle 29.

One of the binding posts 77, to which the input line of a radio set is connected, is directly connected to the loud speaker binding post 73, through the connection 78, while the second radio input binding post 79 is connected through the connection 80 to the stationary contact 62. Thus, upon turning

the handle in the direction of the arrow 81, the movable spring contact 64 will engage, and make electrical contact, with the stationary contact 62, thereby connecting said second radio input binding post with the second loud speaker binding post 75, thereby operatively connecting the radio set with the loud speaker; while the phonograph reproducer is disconnected. Thus, the contacting device 59 has the function of electrically connecting in series with each other the record reproducer, the source of electrical energy, the rheostat and the primary winding of the transformer; as well as to connect in series with each other the loud speaker and the secondary winding of the transformer; of connecting in series, in the opposed extreme position of the handle 29, the radio set and said loud speaker; and to maintain each of these elements electrically disconnected, in the intermediate or neutral position of said handle. These functions are carried out by the two opposed movable spring contacts 63 and 64, which are constantly urged towards each other, by the resiliency thereof, and the separating roller 65 interposed between said spring members, as shown particularly in Figure 9.

By my novel construction in a cabinet, as shown particularly in Figures 1 and 4, in mounting the cone type of speaker in spaced relation to one of the inner walls of the chamber 2, there is obtained a novel combination of cone loud speaker and a tone chamber 2, one wall of which acts as a sound board for said loud speaker, while the other walls surrounding act as a tone or resonating chamber, which directs and amplifies the sound emanating from said loud speaker. The grill front doors permit the sound to be projected out of said tone or resonating chamber, with the front thereof closed and with the loud speaker concealed.

It will be obvious that the collocation of the radio panel 26, and the control panel 25, as shown in Figure 2, imparts a symmetrical, balanced and pleasing appearance to the cabinet front; and I may if desired construct the radio panel 26 as the front of a drawer, (as will be understood from Figure 4,) which contains the various coacting radio elements, assembled within said drawer as a unit, so that to position the radio, it is only necessary to push in the drawer. In like manner, as will be understood from Figures 2 and 7 to 9, the principal control elements of the panel 25 are mounted directly thereon, so that on the removal of the panel all the elements thereon or carried thereby are readily accessible.

It will be apparent that only the single control member 29 is necessary in order to throw in operation, either the radio or the electrical phonographic reproduction, and the rheostat 28 being positioned in proxim-

ity to the control lever 29 enables all the manually operable parts to be compactly assembled in proximity to each other.

While I have shown the radio as being contained in the drawer, so that the coating radio elements can be readily pushed into position or withdrawn as a unit, it will be apparent that my invention is not confined to this precise construction, as any conventional or standard form of radio receiving set may be employed.

It will further be understood that the disc records employed may have the sound reproduced from the grooves in them, mechanically or electrically, and when the electric reproducer seen in Figure 2 is employed, the same functions equally well with either the hill and dale or laterally cut record.

I have further found as a result of extensive experimentation that no vacuum tubes or audions whatever are necessary to be employed in the electric sound reproducing circuit common to the electrical phonographic reproducer, and to the coordinating unit comprising the panel 25 and its adjuncts. By my construction and collocation of the various elements, reproduced sounds of a maximum volume are produced from the disc record without the use of vacuum tubes, and the control of the volume of said sounds is instantly effected by the rheostat 27 and its adjuncts. By my novel construction I am enabled to transmit any sounds or signals locally reproduced from the sound record having its grooves formed either mechanically or electrically, or I can reproduce signals of any character, such as high frequency signals received from a distant station by the radio receiving set by the manual operation of the small lever 29.

It will be apparent that by the elimination of the vacuum tubes or other amplifying means from the circuit leading to the electrically operated phonographic reproducer, both the expense and upkeep of said vacuum tubes is entirely eliminated, so that my device can be operated at a minimum of expense.

It will be evident that the size, shape and contour of the cabinet may be varied according to requirements, but I prefer to employ a small compact cabinet having substantially the contour shown, since the depth from front to rear need be only slightly in excess of the diameter of the turn-table 9, as will be apparent from Figures 4 and 6. By the employment of the cone loud speaker 11 positioned above the turn-table 10, as will be seen from Figures 2 and 4, a very compact structure is attained, and the overall height of the cabinet is reduced to a minimum. The panels 26 and 25 are positioned so as to be readily accessible to a sitting operator, and

the reproduced sounds emanating from the loud-speaker are on about a level with the operator's ear, when in a sitting position and tuning in the radio, as is evident.

It will now be apparent that I have devised a novel and useful construction of combined phonograph and radio, and coordinating unit therefor, which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent is:—

1. A detachable phonograph and radio coordinating unit of the character stated, adapted to be operatively interposed between an electrical record reproducer, a radio receiving set, a loud speaker and a source of electrical energy, comprising a contacting device having an operating handle, a rheostat having an operating knob and a transformer; said rheostat and the primary winding of said transformer being connected in series with a corresponding pair of contacts in said contacting device, and the secondary winding of said transformer being in series with a second corresponding pair of contacts in said contacting device; said contacting device also having a set of contacts to which the output line of said radio set is adapted to be connected.

2. A detachable phonograph and radio coordinating unit of the character stated, adapted to be operatively interposed between an electrical record reproducer, a radio receiving set, a loud speaker and a source of electrical energy, comprising a supporting panel, a contacting device mounted on the back of said panel and having an operating handle extending therethrough, a rheostat mounted upon said panel having an operating knob extending therethrough, and a transformer mounted upon said panel; said rheostat and the primary winding of said transformer being connected in series with a corresponding pair of contacts in said device, and the secondary winding of said transformer being in series with a second corresponding pair of contacts in said contacting device; said contacting device also having a set of contacts to which the output line of said radio set is adapted to be connected.

ALFRED H. HAAG.
